(57) **CLAIM**

The ornamental design for central hub for a digital video disc box, as shown and described.

DESCRIPTION

FIG. 1 is a front perspective view of a central hub for a digital video disc box showing my new design, the box portion being shown in a partially opened position;

FIG. 2 is a perspective view thereof, with the box portion shown in a fully opened position;

FIG. 3 is a top plan view of FIG. 2;

FIG. 4 is a bottom plan view of FIG. 2;

FIG. 5 is an enlarged perspective view of the central hub of FIG. 1; and,

FIG. 6 is an enlarged top plan view of FIG. 5.

The broken line showing the disc box throughout the views illustrates the features that form no part of the claimed design.
